CLAIM

The ornamental design for a baby bottle, as shown and described.

DESCRIPTION

FIG. 1 is a top, front, left perspective view of a baby bottle, shown in a first configuration with bottle cap affixed;

FIG. 2 is a perspective view of the baby bottle of FIG. 1, shown exploded for clarity of disclosure;

FIG. 3 is a front elevation view of the baby bottle of FIG. 1, shown in the first configuration;

FIG. 4 is a left side elevation view thereof;

FIG. 5 is a rear elevation view thereof;

FIG. 6 is a right side elevation view thereof;

FIG. 7 is a top plan view thereof;

FIG. 8 is a bottom plan view thereof;

FIG. 9 is a top, front, left perspective view of the baby bottle of FIG. 1, shown in a second configuration with bottle cap removed;

FIG. 10 is a front elevation view thereof;

FIG. 11 is a left side elevation view thereof;

FIG. 12 is a rear elevation view thereof;

FIG. 13 is a right side elevation view thereof; and,

FIG. 14 is a top plan view thereof.

The equal-length broken lines in the drawings depict portions of the baby bottle that form no part of the claimed design.

1 Claim, 14 Drawing Sheets
